DRAWING INSTRUMENT

Georg Lotter, Neustadt Aisch, Germany

Application September 24, 1952, Serial No. 21,565

Term of patent 14 years

(Cl. D52—1)

To all whom it may concern:

Be it known that I, Georg Lotter, a citizen of Germany, and a resident of Neustadt Aisch, Germany, have invented a new, original, and ornamental Design for a Drawing Instrument, of which the following is a specification, reference being had to the accompanying drawing, forming a part hereof.

In the drawing:

Fig. 1 is a side elevational view of a drawing instrument in open position showing my new design.

Fig. 2 is a similar view showing the drawing instrument when it is closed.

Fig. 3 is an end view thereof.

I claim:

The ornamental design for a drawing instrument, as shown.

GEORG LOTTER.
